CONTINUOUS MINING MACHINE OF THE BORING TYPE HAVING ADJUSTABLE CUTTER CHAINS

Benjamin F. Tracy and James O. Eads, Point Pleasant, W. Va., assignors, by mesne assignments, to National Mine Service Company, a corporation of West Virginia

Application September 24, 1953, Serial No. 382,092

4 Claims. (Cl. 262—7)

Generally this invention relates to a continuous mining machine for mining frangible rocks of the nature of coal, particularly in tunneling operations through coal veins. More specifically the invention relates to upper and lower cusp cutter chains on a continuous coal mining machine and an adjustable mounting for such cusp cutter chains.

Through the years substantial advances have been made in the mechanization of coal mining, such mechanization becoming highly developed, not only for greater safety of the operating personnel in the mine, but also to substantially increase the productive yield of coal from the mine. Thus, in both surface mining and below-ground mining, machines have been developed for producing a substantially continuous mining of the coal from the vein. The hereinafter disclosed invention is particularly concerned with a continuous mining machine specifically adapted for underground mining operations. The continuous operation of this mining machine produces an entry into which the machine moves during mining of the coal from the coal vein.

Generally, the continuous mining machine as described hereinafter utilizes a pair of rotary cutters respectively mounted on the forward ends of a pair of horizontal parallel shafts, which shafts are rotated by driving means carried on the main frame of the mining machine. These rotary cutters during forward movement of the machine into the coal vein cut kerfs in the vein and break down the intervening coal mass to produce parallel cylindrical bores through the coal vein. The bores produced by such rotary cutters overlap one another so as to leave an upper and lower cusp of coal separating the two parallel bores formed by the cutting action of the rotary cutters. To remove these two coal cusps extending downwardly and upwardly from the roof and floor, respectively, of the entry, a pair of endless cutter chains are mounted on the mining machine adjacent but rearwardly of the face of the rotary cutters so as to produce cuts tangent to the uppermost and lowermost points on the bores produced by such rotary cutters. These cuts made by the pair of cutter chains define the roof and floor of the completed tunnel or entry created by operation of the mining machine, and thus clear the entry of the two cusps of coal left by the cutting action of the two rotary cutters. As the mining machine is propelled gradually forward into the coal vein, the coal severed by the combined action of the rotary cutters and the two endless cutter chains is collected from the face of the vein being mined and transported rearwardly of the machine by a traveling conveyor mounted on the main frame of the mining machine.

Operation of the type of mining machine generally described above produces a substantially continuous mining action, in that as the mining machine is propelled slowly forward into the coal vein, the rotary cutters and cutter chains continuously mine away the coal in front of the machine to produce an entry or tunnel suf-

2

ficiently large to enable the machine to move continuously forward into the vein of coal.

Underground coal mining operations expose the mining personnel to a wide variety of ever-present dangers within the mine. Obviously, in utilizing machines to increase the productivity of the coal mining operation, it is of primary importance that such machines be designed and developed with the safety of the operating personnel always in mind. One of the ever-present dangers encountered in underground mining stems from the possibility of settling of the roof of the entry or tunnel in the mine occurring when the machine has not been operated for a period of time, as for example, when the machine stands overnight, or when the roof of the entry falls as a result of the removal of the coal from the vein. Such a settling or roof fall will invariably result in the cutting elements of the mining machine becoming jammed in the entry immediately adjacent the face of the coal vein being mined. Obviously, a sudden roof fall requires that the operating personnel of the mining machine abandon the machine in the interest of their own safety. Subsequently, in salvaging operations or where a minor roof settling or floor upheaval has taken place, it is necessary that the cutting elements of the mining machine be capable of being retracted to decrease the overall dimensions of such cutting elements and thereby enable withdrawal of the mining machine from its wedged position within the mine entry.

Since it is a dangerous operation for the operator and other personnel in the mine to work adjacent the front of the machine to attempt to free the cutting elements so that the machine may be moved from its jammed location, it is extremely desirable for the safety of the operating personnel that the cutting elements be readily retractable and that such retracting may be performed at a point remote from the front of the machine which has become jammed in the entry. In addition to the salvage and recovery advantages of a mining machine wherein the overall dimensions of the mining machine cutting elements may be readily decreased, it is important that the mining machine cutting elements be capable of being retracted to enable free movement of the machine around the mine through restricted entries in transporting the machine from one point of use to another.

Accordingly, it is a principal object of this invention to provide an improved continuous mining machine suitable for mining frangible rocks of the nature of coal which will provide the highest degree of safety for the operators and other personnel in the mine.

It is also a primary object of this invention to provide a coal mining machine wherein the cutter chains which produce cuts defining the roof and floor of the mine entry may be moved from their normal operating positions to facilitate removal of the machine from the mining position and permit movement of the machine through restricted entries within the mine.

It is another object of this invention to provide a mining machine having vertically adjustable upper and/or lower cutter chain guides to enable retraction of the cutter chains from their normal cutting plane.

It is a further object of this invention to provide a continuous mining machine having endless cusp cutter chains traveling in a substantially vertical plane with the upper and lowermost portions of the respective chains traveling in a path which is variable to change the height of entry produced upon operation of the mining machine.

It is another object of this invention to provide a mining machine having a horizontal chain guide which is hydraulically raised and lowered and is capable of being rigidly secured in the desired location for the cutting operation.

It is an additional object of this invention to provide a mining machine having cusp cutter chain guides hydraulically actuatable from a point remote from the cutting face of the machine, which utilizes improved hydraulic actuators designed to effectively preclude the entrance of coal dust thereinto, such actuators being variable by the use of stops positioned to determine the limit of the individual actuator extension.

With the foregoing and other objects in view which will appear as the description proceeds, the invention resides in the combination and arrangement of parts and in the details of construction hereinafter described and claimed, it being understood that changes in the precise embodiments of the invention herein disclosed may be made within the scope of the appended claims without departing from the spirit of the invention.

Referring to the drawings:

Figure 1 is a partial side elevational view illustrating the forward end of the mining machine of this invention.

Figure 2 is a view taken on line 2—2 of Figure 1.

Figure 3 is a detailed elevational view illustrating the mounting of the upper cutter chain guide.

Figure 4 is a sectional view taken on line 4—4 of Figure 3.

Figure 5 is a plan view of the upper cutter chain guide mounting and associated parts as shown in Figure 3.

Figure 7 is a sectional view taken on line 7—7 of Figure 6.

Figure 8 is a sectional view taken on line 8—8 of Figure 6.

Figure 9 is a sectional view taken on line 9—9 of Figure 6, and

Figure 10 is a sectional view taken on line 10—10 of Figure 6.

Referring specifically to Figure 1, there is shown thereon the general features of the mining machine utilizing adjustable cutting elements which cut a tunnel of sufficient size to enable the machine to move thereinto and further permit retraction or decreasing of the dimensions of the cutting elements to permit withdrawal of the machine from a jammed position and/or facilitate the movement of the machine around the mine from the various points of use. The mining machine consists of a main frame 1 which carries all of the coal cutting machinery of the mining machine, including the driving means for the rotary cutters and cusp cutter chains, and the propulsion means for the endless mining machine crawler tracks 2. The main frame 1 is supported on the crawler track frame by four hydraulic trim jacks, one of which is shown at 3 on Figure 1. These trim jacks, positioned adjacent each of the four corners of the mining machine, enable the main frame 1 to be readily adjusted with relation to the crawler tracks 2 so as to position the cutting elements of the machine in the desired relation with respect to the crawler tracks.

The driving means (not shown) for the parallel shafts which support the rotary cutters and for the cusp cutter chains is coupled to suitable gearing housed in a casing 4 mounted on the forward end of the main frame 1. Appropriate gearing within the casing 4 reduces the speed of the driving means and appropriately synchronizes the speed of rotation of the two shafts 5 which are parallel to and spaced on either side of the longitudinal axis of the mining machine. The forward end of each of the shafts 5 has mounted thereon a rotary cutter 6 which preferably is of the type disclosed and claimed in co-pending application Serial No. 374,910 filed August 18, 1953, now abandoned. The rotary cutter 6 secured on the shaft 5 is provided with an actuating means 7 which is manually operated to decrease the length of the rotary cutters from a point remote from the face of the mining machine. The operation and purposes of this adjustable

rotary cutter are fully set forth and described in the above noted application.

The individual rotary cutters 6 mounted on the forward ends of the parallel shafts 5 are synchronized through the gearing within the casing 4 so that during the cutting operation they produce the parallel overlapping bores, the diameter of which determines the size of the final entry produced by the mining machine. Generally, each rotary cutter 6 is characterized by having a central pilot bit 8 and radially spaced kerf cutting bits 9 mounted on the radial arms of the rotary cutter. A swaging member 10 is carried by the pilot bit 8 so as to enter the bore produced by such bit and wedge the coal material outwardly to break free the frangible rock material between the bore made by the pilot bit 8 and the innermost kerf cutting bits 9. Adjacent the kerf cutting bits 9 there is supported a breaker roller 11 mounted so as to engage the side of the annular mass of coal material remaining between the kerf cutting bits 9 to effect breaking of this mass of coal from the face of the vein being mined. A shovel plate 12 is also mounted on each end of rotary cutter 6 adjacent the kerf cutting bits 9 on the side opposite the breaker roller 11.

To move the mass of coal which is cut and broken away from the face of the vein being mined, a traveling conveyor 15 is mounted intermediate the mining machine crawler tracks 2 to extend from a point adjacent the forward end of the machine near the floor level of the mine upwardly and rearwardly to the rear end of the mining machine. This conveyor collects the coal from the front of the machine as deposited in its intake by shovel plates 12 on the rotary cutters 6, and transports it rearwardly for loading into mine cars or other means to remove the coal from the point of mining.

The cutting action of the two overlapping rotary cutters 6, as hereinbefore described, leaves an upper and lower cusp of coal extending respectively downwardly and upwardly from the roof and floor of the mine entry. In order to enable the mining machine to completely move into the tunnel or entry which it is cutting into the coal vein, it is necessary that these two coal cusps be cut and removed from the tunnel being mined. To perform this cutting and removing action, a pair of endless cutter chains 20 and 21 are mounted adjacent but rearwardly of the cutting face of the rotary cutters 6. These two endless cutter chains produce cuts which define the roof and floor of the mine entry into which the machine gradually moves during continuous operation of the miner. The path of these two cutter chains generally lies in a vertical plane immediately behind the two rotary cutters 6. The path of travel of these two chains is best illustrated by the view shown in Figure 2, wherein it will be noted that the cutting portion of the path of travel of the cutter chains 20 and 21 is supported and guided by an upper chain guide 22 and a lower chain guide 23, respectively.

The lower chain guide 23 is mounted to extend beneath front plates 24 positioned at each side of the entrance to the conveyor 15. These plates 24, attached to the forward end of the miner, function to hold or confine the loose coal broken from the coal vein face by the action of the cutting elements of the mining machine so as to be swept toward the mouth of the conveyor 15 by the shovel plates 12 on the ends of the rotary cutters 6 as such rotary cutters revolve to cut into the coal vein.

Idler pulleys 25 are carried by the lower chain guide 23 at the opposite ends thereof around which the cutter chain 21 extends in traversing its path upwardly across the face of the mining machine. The chain guide 23 is mounted for adjustment relative to the other mining elements carried on the main frame 1 by suitable hydraulic actuators 26. These hydraulic actuators, connected between the main frame 1 and chain guide 23 may be actuated as desired by controlling the flow of hydraulic

fluid thereto, through appropriate manipulation of valves on the hydraulic manifold mounted adjacent the operator of the mining machine.

In the embodiment shown on the drawings, hydraulic actuators 26 serve as the mounting for the lower chain guide 23 and idler pulleys 25 to enable adjustment of the lower chain guide relative to the floor of the mine entry. However, as previously described, the main frame 1 is mounted on four hydraulic trim jacks 3 by means of which such main frame may be suitably positioned with relation to the crawler tracks 2 of the mining machine. Therefore, if desired, the hydraulic actuators 26 may be omitted and the chain guide 23, which carries the pulleys 25, rigidly mounted, as by bolting, on the forward end of the mining machine. Then the trim jacks 3 will be used to adjust the lower chain guide relative to the mine floor. By such rigid mounting of the chain guide 23, as by bolting or welding it to the front of the miner, the necessary adjustment of the level of the lower chain guide 23 may be secured by using the hydraulic trim jacks 3 to raise or lower the main frame 1 with respect to the crawler tracks 2.

The lower cutter chain 21 extends upwardly from its horizontal cutting path across the front face of the mining machine to drivingly engage a driving sprocket 30 which is suitably secured on the outer end of a shaft 31 extending through the front of the gear casing 4 and driven at an appropriate speed by the main driving means coupled through the gearing in the casing 4. A tensioning sprocket 32 is journaled on the outer end of a stub shaft 33 mounted on a support 34 which in turn is pivotally supported behind the driving sprocket 30 so as to be movable about the axis of the shaft 31. The support 34, which carries the tensioning sprocket 32 on the stub shaft 33, is continuously urged about its support axis by a tensioning device 35 secured to the front of casing 4 so that the tensioning sprocket will be urged into engagement with the cutter chain 21 to continuously maintain such chain taut about the driving sprocket 30, idler pulleys 25 and chain guide 23.

It will be readily recognized that rotation of the shaft 31 through the appropriate gearing in the casing 4 will cause the cutter chain 21 to move along the path, as outlined on Figure 2, with the portion of such path extending between the idler pulleys 25 forming the cutting portion of the chain to remove the lower coal cusp during operation of the mining machine in a coal mine. The tensioning device 35 at all times urges the sprocket 32 to wrap the cutter chain 21 further around the driving sprocket 30 to keep such cutter chain taut and in driving engagement with the sprocket 30.

The upper cutter chain 20 travels in a path lying in a vertical plane similar to the path traversed by the lower cutter chain 21. The upper cutter chain 20 is supported and guided during the portion of its path wherein cutting is performed by the upper chain guide 22. The opposite ends of the upper chain guide 22 have journaled thereon idler pulleys 49 similar to the idler pulleys 25 adjacent the ends of the lower chain guide 23. The path of the cutter chain 20 extends down around a driving sprocket 41 mounted on a shaft 42 extending from the casing 4 wherein it is suitably coupled to the main driving means of the mining machine so as to be driven thereby. A tensioning sprocket 43 is journaled on a stub shaft 44 carried by a support 45 pivotally mounted so as to be movable about the axis of the shaft 42, and a tensioning device 46 is secured to the front face of the casing 4 to continuously urge the tensioning sprocket 43 against the cutter chain 20 to maintain such chain taut and in driving engagement with the driving sprocket 41. Thus the operation of the upper cutter chain 20 is substantially identical to that of the lower cutter chain 21 in being driven by the sprocket 41 coupled to the shaft 42 which is rotated at the proper speed by the gearing within the casing 4.

To support the upper chain guide 22, a pair of hydraulic actuators 50 are secured between lugs 51 on the ends of the guide 22 and brackets 52 mounted on the front face of the casing 4 adjacent the bearings for the shafts 5 on each side of the mining machine. These hydraulic actuators 50 are pivotally interconnected at their respective ends with the lugs 51 and brackets 52 so that when hydraulic fluid pressure is applied to such actuators, it will cause raising or lowering of the upper chain guide as may be desired during appropriate manipulation of the mining machine.

Cooperating with the hydraulic actuators 50 to guide the movement of the upper chain guide 22 during raising and lowering thereof by the supporting hydraulic actuators 50, there are provided guide arms 55, bolted to the underside of each end of the chain guide 22, with the guiding surfaces thereof extending vertically with respect to the normally horizontal chain guide. A guide rail 56 having a mating surface to engage the vertical guide surface of the guide arm 55 is bolted to the front face of the casing 4 at each side thereof and a notched positioning plate 59 bolted to the top of the casing 4 to extend outwardly over the edge thereof and maintain the rail 56 with its guide engaging surface substantially vertical to cooperate with the guide arm 55.

As more clearly illustrated in Figure 4, the guide surface of the arm 55 is provided with a ridge 57 which cooperates with a groove 58 in the surface of the guide rail 56. This cooperating ridge and groove construction between the arm 55 and the rail 56 provides a support construction for the upper chain guide 22 which in cooperation with the supporting hydraulic actuators 50 will resist the rearward thrust applied to the chain guide during operation of the mining machine when the cutter chain 20 is cutting into the upper coal cusp.

The arms 55 and rails 56 are provided with a series of apertures 60 which, upon relative movement between the respective arms and rails, become aligned to enable the insertion of locating bolts 61 to rigidly secure the upper chain guide in its desired location with respect to the parts of the mining machine. Obviously, however, during raising and lowering of the upper chain guide 22 by the supporting hydraulic actuators 50, the bolts 61 will not be in place, so that the arms 55 will slide relative to the rails 56 mounted on the front face of the casing 4. Likewise, during various other conditions of use, locating bolts 61 need not be employed, at which time the arms 55, by cooperation with the rails 56, will serve to effectively guide and maintain the upper chain guide 22 horizontal during raising, lowering, and/or while in use.

To provide additional support to resist the thrust encountered during cutting with the chain 20, the upper chain guide 22 is further provided with lugs 65 at each end which carry pins 66 extending from each side thereof. Brackets 67 are secured to the top face of the casing 4 to pivotally support diagonal struts 68 which each carry a yoke 69 at the opposite end thereof to engage the respective pins 66 and lugs 65 on the upper cutter chain guide 22. The length of the diagonal strut 68 is variable by means of a nut 70 threaded onto the rod which carries the yoke 69 and adapted to engage the end of the sleeve into which such rod slides and which is pivotally carried by the bracket 67. Thus, it will be seen that once the chain guide 22 has been positioned at its desired height, the additional thrust resisting support provided by the diagonal struts 68 may be brought into use by threading the nut 70 down into engagement with the end of the sleeve of the strut so that the diagonal struts will provide thrust resistance for the cutter chain in addition to the thrust resistance offered by the engaging relationship between the arms 55 and rails 56.

With the hereinabove described structure, it can readily be appreciated that the upper path of travel of the cutter chain 20 may be lowered or raised by suitably

moving its horizontal chain guide 22. This chain guide is supported by the hydraulic actuators 50 at each end thereof and is guided during its raising and lowering by both the actuators 50 and engagement of the arms 55 with the rails 56. The engagement of these two latter members provides a thrust resisting support for the cutter chain 20 to which is added the support of the diagonal struts 68 which are adjustable in length to accommodate the varying diagonal distances encountered when the chain guide 22 is at the various levels of adjustment.

Generally, it is contemplated that the upper chain guide will be used at a particular location correlated with the specific location of the lower chain guide 23 and the length of the rotary cutters 6. This location is determined by the height at which the cutter chain 20 will make a cut in the frangible rock material which is tangent to the circles scribed by the two overlapping rotary cutters 6. Thus when the hydraulic actuators 50 are fully extended the chain guide 22 is at its proper height to guide the chain 20 in cutting the roof line of the entry, tangent to the top of the bores cut by rotary cutters 6. When the upper chain guide 22 is to be lowered, if the adjustable diagonal strut 68 and the locating bolt 61 have been utilized to rigidly support the chain guide in its extended position, it is merely necessary to loosen the nut 70 on each of the diagonal struts 68, remove the locating bolts 61 between the arms 55 and rails 56, and then lower the chain guide to the desired position by means of the supporting hydraulic actuators 50.

At the same time that the upper chain guide is lowered, the rotary cutters 6 will be retracted by manipulation of the individual actuating means 7 for each rotary cutter. This combined action will reduce the overall dimensions of the cutting elements of the mining machine to enable its free withdrawal from the face of the vein being mined and/or permit the machine to be moved about the mine through restricted entries therein. To insure that the lower chain guide 23 and its cutter chain 21 are free of obstructions on the mine floor, the lower chain guide and idler pulleys 25 carried thereby may also be raised by appropriate control of hydraulic fluid pressure to the hydraulic actuators 26. This will effect a further reduction in the overall dimensions of the cutting elements of the miner. When the chain guide 23 is bolted to the forward end of the miner with the hydraulic cylinders 45 omitted, the trim jacks 3 which support the main frame 1 on the crawler tracks 2 may be used to raise the lower chain guide and cutter chain along with main frame 1 so as to clear the floor of the mine entry during movement of the mining machine.

Figures 6 through 10 illustrate an alternative form of support for the upper chain guide 22, wherein the guide is supported by a pair of hydraulic actuators and guided by a guide means cooperating with the hydraulic actuators as in the previously described embodiment. As will be apparent from the description that follows, these hydraulic actuators are of an improved construction and so related to the upper chain guide 22 as to effectively preclude the entrance of coal dust or other foreign material into the moving parts of the actuator. Figure 6 illustrates one of such supporting hydraulic actuators in its relationship to the chain guide 22 and the front of the casing 4 on which it is mounted. It will be understood that as in the previously described embodiment, there are two supporting actuators for the chain guide 22, one at each end thereof.

In this modified form, a supporting shelf 80 is suitably secured to the front face of the casing 4 as by welding, to provide an abutment to be engaged by the end of a plunger 81, the lower end of which rests on the shelf 80 and is suitably retained in position thereon to provide a pocket for the end of the plunger 81. The lower end of the plunger 81 is suitably tapped to receive a fitting to which is coupled the hydraulic fluid line 83 which

serves to admit the hydraulic fluid into the plunger 81 to effect actuation of the hydraulic actuator as hereinafter described.

The plunger 81 is telescoped into a cylinder 84 which is connected to the underside of the chain guide 22 by a pin 85 engaging a bracket 86 bolted to the underside of such chain guide adjacent the end thereof. The cylinder 84 is provided with a suitable packing gland 87 to prevent leakage of hydraulic fluid from the interior of the cylinder 84 and plunger 81 during use of the hydraulic actuator.

Cooperating with the hydraulic actuators to guide movement of the upper chain guide 22 there are provided guide members 90 each having a slot 91 to receive one of the cylinders 84 therein and secured as by welding to the front face of the casing 4. Each cylinder 84 has wings 92 which extend along a portion of the length of the cylinder and slide in the slot 91 in the guide 90. Flanged strips 93 are secured by bolts 94 along the opposite sides of each slot 91 to engage the wings 92 of the cylinder 84. Thus a pocket is formed to slidingly receive the wings 92 on the cylinder. This pocket construction in the guide members 90 effectively guides the cylinders 84 to restrain their moving of the chain guide 22 to take place in a vertical plane with the chain guide remaining horizontal. The guiding action of guide members 90, together with their support by the hydraulic actuators offers an extremely strong and rigid mounting means for the upper chain guide, similar to the mounting described with regard to the first embodiment.

The flanges on strips 93 extend into slot 91 so as to engage the outer side of the wings 92 as shown most clearly in Figure 8. However, a portion of these flanges adjacent the top of guide member 90 extends further into slot 91 to form limiting abutments 97 for the upper ends of wings 92 to engage and prevent the cylinder 84 from unduly raising the chain guide 22. Thus these abutments 97 determine the uppermost limit for raising the upper chain guide.

To vary the upper limit of the hydraulic actuators shown in Figures 6 through 10, there is provided stops 95 which fit into the space in the slide pocket provided for the wings 92. These stops are secured below the limiting abutments 97 by screws 96, and when so positioned and engaged by the upper ends of wings 92, determine the upper limit of the cylinder 84 in raising the upper chain guide 22. A plurality of tapped bores are provided along the strips 93 as shown on Figure 6 to accommodate the screws 96 and permit the stops 95 to be secured in the pocket for wings 92 at any one of a number of positions depending on the desired upper limit for the chain guide 22.

In the use of the hydraulic actuators of the modification shown in Figures 6 through 10, the hydraulic fluid admitted through line 83 causes the cylinder 84 to move to its extended position limited by engagement of the wings 92 with abutments 97 at the upper ends of the strips 93, or, if present, stops 95. In operation of the miner with this modified chain guide mounting, the cutting elements are retracted similarly to the operation of the previously described embodiment. The hydraulic actuators support the chain guide, and the wings 92 on the sides of the cylinders 84 cooperate with guide members 90 to properly guide the raising and lowering of the chain guide. Thus hydraulic pressure applied through line 83 will propel the hydraulic actuators to their limit of travel to position the upper cutter chain for use. Likewise on release of the hydraulic fluid by proper manipulation of the manifold valves adjacent the mining machine operator the cutter chain will be lowered. The rotary cutters will also be retracted by actuating means 7 so that the cutting elements of the miner will be contracted to enable the miner to be readily moved from mining position and/or be transported through the mine

entries. It will be appreciated that the lower chain guide 23 may be raised by employing hydraulic cylinders 26, if present, or by utilizing the trim jacks 3 to clear the cutter chain 21 above the mine floor.

In addition to the increased safety to mine personnel offered by the mining machine of the hereinabove-described invention, the flexibility of use is substantially increased. The ability to contract the cutting elements of the mining machine with the retracting operation being performed at a point remote from the cutting face of the mining machine promises safe mine operating procedures, since the operator or other mine personnel need not subject themselves to the hazards of working adjacent the cutting face where roof settling may have occurred or may occur while they are working on the machine. Likewise, the adjustability of the relationship between the various cutting elements of the mining machine permits the machine to be readily adjusted to produce a variety of different size entries, depending on the settings of the cutting elements. Thus the stops 25 may be employed to vary the upper limit of the chain guide 22 and the rotary cutters 6 adjusted to correspond to the diameter necessary to cooperate with the plane of the upper cutter chain at its limit. By the same token the lower cutter chain may be adjusted by hydraulic cylinders 26 to be tangent with the bores produced by the new setting of the rotary cutters 6 or be adjusted by relocating the chain guide 23 as bolted on the forward end of the miner in the absence of hydraulic cylinders 26.

Having thus described our invention, what we claim is:

1. A mining machine comprising a main frame, a crawler track frame having a pair of propelling crawler tracks, means supporting said main frame on said crawler track frame to permit relative adjustment therebetween, a pair of parallel horizontal shafts carried by said main frame, rotary cutters respectively mounted on the forward ends of said shafts to cut parallel horizontal bores during operation of said mining machine, a cutter chain having an effective cutting portion normally extending tangent to said parallel bores, a chain guide engaging and supporting the effective cutting portion of said cutter chain, a pair of elongatable hydraulic actuators each having a cylinder and a plunger telescopically engaging said cylinder, said cylinders being secured to the opposite ends of said chain guide respectively to move therewith during raising and lowering of said chain guide and the plungers cooperating respectively with said cylinders being supportingly engaged with said main frame to be stationary with respect thereto, means for coupling a controlling hydraulic fluid to said cylinders to effect raising and lowering of said chain guide relative to said main frame, and guide members secured to said main frame each having a slot extending longitudinally thereof, one of said cylinders being slidably received in each of said guide members, said guide members guiding the movement of said cylinders in positioning said chain guide relative to said main frame to restrain said chain guide to move in a vertical plane during raising and lowering thereof under control of said actuators and resist rearward thrusts imparted to said chain guide in use of the mining machine.

2. In a mining machine of the type having rotary cutters mounted on the forward end of the machine rotatable in a vertical plane to cut parallel overlapping cylindrical

bores in the material being mined, a cutter chain having an effective cutting portion thereof normally extending substantially tangentially to the parallel cylindrical bores, an elongated chain guide supporting said effective cutting portion, a first elongatable hydraulic actuator having a pair of slidably telescoping members with one of said members connected to and movable with one end of said chain guide and the other member supported on the forward end of the mining machine to be stationary with respect thereto, a second elongatable hydraulic actuator having a pair of slidably telescoping members with one of said members connected to and movable with the other end of said chain guide and the other member thereof supported on the forward end of the mining machine to be stationary with respect thereto, a pair of spaced parallel guide members rigidly mounted on the forward end of the mining machine beneath the opposite ends of said chain guide respectively, each of said guide members having a vertically extending longitudinally grooved guide surface, each of the members of said first and second elongated hydraulic actuators which are connected to and movable with said chain guide being slidably engaged with the vertically extending guide surface of one of said guide members to restrain said chain guide to move in a vertical plane during raising and lowering thereof under control of said actuators and resist rearward thrusts imparted to said chain guide in use of the mining machine, and means cooperating with the engaging guide members and members of said hydraulic actuators movable with said chain guide to limit upward movement of said chain guide, said means being selectively adjustable to alter the upper position of said chain guide.

3. In a mining machine as recited in claim 2 further comprising a second cutter chain having an effective cutting portion thereof normally extending substantially tangent to the cylindrical bores on the side thereof diametrically opposite the points of tangency of the first cutter chain, a second chain guide engaging and guiding the effective cutting portion of said second cutter chain, and hydraulic actuators mounting said second chain guide to permit limited movement of said cutting portion of said second cutter chain away from its normal position.

4. In a mining machine as recited in claim 2 wherein the members of said hydraulic actuators movable with said chain guide have longitudinal wings on the sides thereof slidably engaged in the longitudinal grooves of said guide members, and abutments are provided at the ends of the grooves in said guide members to be engaged by the ends of said wings to limit movement of said chain guide.
